ABSTRACT OF THE DISCLOSURE

A dish-washing machine spray head having a cylindrical body arranged for rotary and oscillatory movement on which a pair of outwardly projecting tubular ducts are mounted. The head is provided with another pair of ducts having axes which intersect above the head to form a sheet of washing liquid when pressure is applied.

The present invention relates to a dish-washing machine having a water projecting device in the form of a substantially cylindrical body provided with a distribution chamber and an apertured head and arranged for rotary and oscillatory movement imparted to it by water pressure.

A water projecting device of this type is described in French patent specification 1,321,499.

This device has the disadvantage that since the water projection is performed solely from the center of the tub, some pieces to be washed, arranged at the corners or near the walls of the tub are beyond the range of the jets, so that they are not washed satisfactorily.

The present invention obviates this disadvantage and is characterized in that at least one water outlet duct is associated with the wall of the distribution chamber.

In an embodiment of the machine according to the invention the free end of the duct is at least partly closed, while the wall of this duct has at least one aperture. It another embodiment the sum of the areas of the apertures provided in the wall is smaller than the surface of the cross sectional area of said duct.

In another embodiment of the dish-washing machine according to the invention the free end of the duct is closed by a flat surface which is at an angle of about 60° to a cross sectional plane of the tube.

In still another embodiment of the invention a tube communicates with at least one of said apertures provided in the wall of said duct and that a cross sectional plane of the tube is at an angle of about 80° with a cross sectional plane of the duct.

In an advantageous embodiment of the dish-washing machine according to the invention, in which the wall of the distribution chamber is cylindrical, there are provided two ducts extending perpendicularly to said wall. Since the cross section of the distribution chamber is circular, said two ducts communicate with two diametrically opposite apertures provided in said wall.

The invention will now be described more fully with reference to the accompanying drawing.

FIG. 1 is a sectional view of a water projection device for a dish-washing machine according to the invention.

2

FIG. 2 is a partial plan view of this water projection device.

The device according to the invention comprises mainly a nozzle 1, a supporting member 2 and a guide 3. The supporting member 2 is internally provided with a conical seat 4, by means of which it bears on a pipe 5, which is traversed by the high-pressure washing liquid. The supporting member 2 is provided with a collar 7, which partially covers the supply pipe 5 and with which is connected a shoulder 8, which projects to the outside and is in contact with the inner face of the guide 3 and rolls along said face when the washing liquid is supplied under pressure. This liquid passes through the supply pipe 5, arrives in the distribution chamber 9 and emerges partly through the ducts 10 of the nozzle 1—these ducts being disposed so that they impart a rotary and oscillatory movement to the device—and partly through the ducts 18, the axes of which coincide, so that the jets are transformed into a liquid sheet. The pressure energy of this sheet exerted on the dishes arranged directly above the device is lower than the force which would be exerted by the direct jets.

According to the invention the wall 11 of the distribution chamber 9 has secured to it two tubes 12 and 13, one of the ends of which is closed by a plate 14. It is preferred for the plate 14 to be at an angle of about 30° to the cross sections of the tubes 12 and 13. The walls of the latter are provided with apertures 15. Two tubes 16 and 17 are welded to the peripheries of two openings 15. The axes of symmetry of the tubes 16 and 17 are at an angle of about 80° to the axes of symmetry of the tubes 12 and 13.

What is claimed is:

1. A dish-washing machine spray head comprising a substantially cylindrical body provided with a distribution chamber, means forming a fluid inlet to said distribution chamber, said body having a first fluid outlet communicating with said chamber and arranged for imparting rotary and oscillatory movement to said body, said body having a pair of fluid outlets communicating with said chamber and having axes intersecting above the body for forming fluids flowing therethrough into a fluid sheet, and a tubular water outlet duct radiating outwardly from the wall of the distribution chamber.

2. A dish-washing machine as claimed in claim 1 wherein the free end of the tubular duct is at least partly closed, and wherein the wall of said duct has at least one aperture.

3. A dish-washing machine as claimed in claim 2 wherein an end of the duct is closed by a flat surface which is at an angle of about 60° to a cross sectional plane of said duct.

4. A dish-washing machine as claimed in claim 3 wherein a tube communicates with at least one of said apertures provided in the wall of said duct, and wherein a cross sectional plane of the tube is at an angle of about 80° with a cross sectional plane of the duct.

5. A dish-washing machine as claimed in claim 2 wherein the wall of the distribution chamber is cylindrical and wherein the two tubular ducts are arranged perpendicularly to said wall.

6. A dish-washing machine as claimed in claim 5 wherein a cross section of the distribution chamber is circular and wherein said two tubular ducts communicate
